UNITED STATES PATENT OFFICE.

LOUIS A. CASGRAIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR INSERTING FASTENINGS.

1,361,013.

Specification of Letters Patent.

Patented Dec. 7, 1920.

Application filed July 5, 1917. Serial No. 178,623.

to all whom it may concern:

Be it known that I, LOUIS A. CASGRAIN, a citizen of the United States, residing at Beverly, in the county of Essex and State of

5 Massachusetts, have invented certain Improvements in Machines for Inserting Fastenings, of which the following description, in connection with the accompanying drawing, is a specification, like reference characters on the drawings indicating like parts in the several figures.

The invention hereinafter described relates to machines for operating on boots and shoes and, while it comprehends principles 15 of construction and operation especially applicable to the insertion of fastenings in the heels of boots and shoes, it is applicable to fastening-inserting machines in general and to shoe making machines of other types.

20 The term "fastening" is herein used for the sake of brevity, in its broad and general sense, and includes devices and means for uniting either temporarily or permanently the parts into which they are inserted 25 or for purposes of ornamentation or resisting wear. In the following exposition of the invention it will be described in connection with a machine for inserting fastenings into the heels of boots and shoes, such, for instance, as that described in the patent to Casgrain, No. 1,053,479, but it is to be understood that the present invention is not limited to machines of the character disclosed by said patent.

30 It is frequently desirable when a tool or tools is caused to operate on a shoe that the points of operation of the tool on the work be spaced at uniform distances from each other. For example, when a series of fastenings is inserted into a boot or shoe part, such, for instance, as the heel of a shoe by fastening inserting tools or instrumentalities the fastenings should preferably be uniformly spaced with relation to each other, and the same uniformity of spaced relation should be maintained in heels of different dimensions. Where such series of fastenings is to be arranged in a curved line, such, for instance, as long or parallel to the contour edge of a heel, difficulty is experienced in maintaining the desired uniformity in the spaces between adjacent fastenings when the dimensions of the heels vary, because the angular feed movement of the work appropri-

55 ate to space the fastenings properly in a heel of one dimension will not be suited to maintain the same spaced relation of fastenings in a heel of different dimension.

An important feature of the present invention consists in means for feeding the work support variable angular amounts determined by a dimension of the work supported by it. This feature of the invention may be variously embodied. As illustrated, it is embodied in an organization comprising 65 a work support and a gage for positioning the work, together with a feeding means for the work support constructed and arranged to permit the operative relation of the work support and feeding means to be varied 70 in accordance with a dimension of the work.

Another important feature of the invention consists in means for preventing movement of the work support between feed movements regardless of the amplitude of the feed movements. In the illustrated embodiment of the invention this is effected by a clamp or holder, which, during feed movements, is 75 inoperative, but between feed movements is 80 automatically actuated to clamp the work support and hold it from accidental movement.

During the operation of the machine, it is also desirable that the heel or other part of 85 the shoe being operated upon be held firmly against the gage or other device which positions the shoe relatively to the operating tool or tools, and yet that the shoe be readily movable toward and from the gage when the 90 machine is at rest to permit the work to be moved into and out of operative relation to the operating mechanism. A further important feature of the invention consists in a work support freely movable to place the 95 work against the gage while the machine is at rest and means acting automatically when the machine is started to force the work yieldingly against the gage. As shown herein, this feature is embodied in a spring connection 100 between the shoe support and means operative upon starting the machine to place the spring under tension.

Since economic production renders it desirable that the operation on the shoe be carried on with as little interruption as possible consistent with a proper supply of work by the attendant, in accordance with another

feature of the present invention, the illustrated machine is provided with a shoe support comprising a carrying plate or member operatively associated with a machine part 5 and a plurality of jacks of novel construction which may be readily applied singly to the carrying plate or member, so that while one shoe is being operated upon the attendant may be jacking another shoe ready 10 to be secured to the carrying plate or member as soon as the current operations have been completed.

It is furthermore important that the points 15 of operation be arranged at uniform distances from the edge of the heel or shoe part upon which operations are being performed and, to insure this relation of the operating means and the edge of the work, another feature of the invention consists in novel 20 means for guiding the work support during its feed movements in a path substantially similar to the contour of the heel or other shoe part.

Where the shoe support, as in the illustrated form of the invention, is not raised and held raised during the insertion of a fastening and then lowered to permit feed of the work, it is desirable to adjust the shoe on the jack in such position that, when the 25 jacked shoe is transferred to the carrying plate or member, the tread surface of the heel may pass beneath the foot plate and yet be in such close proximity thereto that, when the foot plate is depressed during the 30 insertion of a fastening, it will firmly engage and press upon the tread surface of the heel. The present invention comprises also as one of its important features a jack of novel construction and means for determining the position of the shoe on the jack 35 so that the tread surface of the heel may pass beneath the foot plate when the jacked shoe is transferred to the carrying plate or member.

The invention comprises other features 40 which, in addition to those above referred to, will be fully described in connection with the accompanying drawings, which show one good, practical form of means for carrying the several features of the invention into effect, and the several features of the invention will then be definitely set forth in the claims.

In the drawings:—

Figure 1 is a side elevation of a fastening-inserting machine containing the present invention;

Fig. 2 is an enlarged plan view of a portion of the work support, and its actuating means, for feeding the work, some of the parts being broken away;

Fig. 3 is a sectional elevation on the line 3—3, of Fig. 2, some of the parts being broken away;

Fig. 4 is a detached perspective view,

showing the general relation of parts and their operative connections, the framework being omitted and some portions being broken away for clearness of illustration;

Figs. 5, 6 and 7 are detached face views of 70 certain cams for actuating parts to be described;

Fig. 8 is a detached detail in perspective showing the means for placing the work support under yielding pressure with the 75 work against the gage;

Fig. 9 is a side of the jack showing by full lines a shoe supported thereon in jacked position, and in dotted lines the heel seat clamp thrown back for unjacking the shoe; and 80

Fig. 10 is a view similar to that of Fig. 9, but showing some of the parts in section and others broken away to disclose the structure beyond.

A base or standard 1 of suitable character 85 supports a head 2 in which is suitably mounted a main driving shaft 3. Upon the main driving shaft 3 are the fast and loose pulleys 4 and 5 which may be connected by suitable means such as a belt, to any desired 90 source of power. When the machine is in use, the belt will be shifted from the loose pulley 5 to the fast pulley 4, so that the main driving shaft 3 will be continuously rotated. Secured to the main driving shaft 3 is a cam 95 disk 6, the cam groove of which is engaged by a pin or roll carried by an arm 7 suitably mounted to rock on the head frame. The head frame 2 carries the foot plate 8 which, during the insertion of a fastening 100 into the work, is lowered to rest upon the work and impart some degree of pressure thereto. An edge gage 9 is carried by the head frame and serves to position the work relatively to the fastening-inserting mechanism by engagement with the contour surface of the work. In case the fastenings are to be inserted into a heel, the edge gage 105 9 will contact with the contour surface of the heel, and serve to guide the heel as the 110 latter is moved or fed along the edge gage to position the work for the insertion of fastenings in succession. The parts so far described, as well as the means for operating on the work to insert fastenings therein 115 may be substantially of the same character and construction as those disclosed in the Casgrain Patent, No. 1,053,479. The machine of the said patent makes and inserts the fastenings; but it will be understood 120 that the present invention, while applicable to a machine of this type, is equally applicable to machines which insert previously formed fastenings.

Rising from the base or standard 1 is a 125 support 10 having arms 11 for sustaining a table 12 on which is adapted to rest the carrying plate or member 13 of the work support. When the work is placed upon the work support, the construction of which will 130

be hereinafter described, it is desirable that the work support be movable to place the edge of the work or the heel against the back gage and in operative relation with the 5 fastening - inserting mechanism, and that after the work has been placed in such operative position relative to the fastening-inserting mechanism, that it be given a step-by-step feed movement for the insertion of 10 fastenings in desired design into the work. Obviously, the size or contour shape of a heel will determine the position to which the work is moved to bring it into operative relation with the fastening-inserting mechanism; and since the size and contour of heels 15 differ, the step-by-step feed movements given to the work support which will be suitable for one character or size of heel will be unsuitable for another size or character of heel. The present invention, therefore, contemplates that the angular step-by-step movements imparted to the work shall be variable in amounts as determined by a dimension of the work in order to insure 20 that similar intervals be maintained between the fastenings when driven into heels of different sizes or contours.

The feeding means for imparting the step-by-step movement to the work support may 30 be variously contrived, but in the present instance of the invention it comprises an actuating arm 14 pivotally mounted at 15 to a fixed part of the machine frame and connected by a link 16 to an arm 17 extending 35 from a rock-shaft 18 supported in suitable bearings 19 sustained upon the head frame of the machine, and actuated from the main driving shaft 3 through suitable connections such, for instance, as the arm 20 secured to 40 the rock-shaft 18 and connected at its free end to the rod 21. The rod 21 at its upper portion is connected at 22 to a rocker arm 23 pivoted on a supplemental shaft 24 and having at its upper end a pin or roll 25 engaging 45 a suitable cam groove 26 in a cam secured to the main shaft. In the present instance of the invention the cam groove 26 is formed in the face of the fast pulley 4. From the construction described it will be 50 apparent that when the main driving shaft 3 is operated, the arm 14 of the feed mechanism will be continuously operated or reciprocated on its pivotal mounting 15.

Extending downwardly from the carrying plate or member 13 of the work support is the spacer 27, Fig. 3, having at its lower portion and spaced some distance from the carrying plate or member 13, the flange 28. The arm 14 of the feeding means is bifurcated at 29 as indicated in Fig. 3 and the flange 28 extends into the bifurcated portion of the arm, the construction being such that should the carrying plate or member 13 be moved bodily relative to the feeding means, the position of the flange 28

within the bifurcated portion of the arm 14 will be changed and the degree of change will be dependent upon the amount of relative movement given to the carrying plate or member 13. As hereinbefore noted, the 70 carrying plate or member 13 is a part of the work support on which is mounted the work into which fastenings are to be inserted; consequently, when the carrying plate or hub 13 with the work mounted 75 thereon is moved relative to the feeding means or the arm 14 to place the contour edge of the work against the edge gage, the flange 28 of the carrying plate or member 13 will be moved more or less into the bifurcated portion 29 of the arm 14.

In order that the actuating arm 14 of the feeding means may be operatively connected to the flange 28 of the carrying plate or member 13 as the actuating arm 14 makes 85 its active stroke and be released from such operative connection when the actuating arm makes its inactive stroke, the present invention provides means for effecting operative relation of the actuating arm with 90 the flange 28 only when said actuating arm is making its active stroke. This feature of the invention may obviously be carried into effect by various detail forms of means, but in the present instance of the invention, 95 a wedge carrying plate 30 is mounted to rock upon the pivot, 15, Fig. 3, and carries a wedge portion 31 on which rests a pin 32 passing through the perforation in the actuating arm 14 and adapted to engage one side of 100 the flange 28 of the work carrying plate or member 13 when the wedge plate 30 is moved to cause a high part of the wedge 31 to pass beneath the pin 32. The upper portion of the actuating arm 14 may be provided with a friction piece 33 between which and the upper end of the pin 32 the flange 28 may be clamped when the wedge plate 30 is properly actuated. In order further to insure an equal spacing of the fastenings 110 regardless of variations in the sizes of the heels, the friction piece 33 and pin 32 are disposed to engage the flange 30 at the end of their feeding movements at points substantially in line with the fastening driver. 115

The wedge plate 30 is connected by a link 34 to a block 35 movable in a slot 36 formed in the upper portion of an actuating arm 37 projecting from the rock shaft 38, Fig. 4. The rock shaft 38 may be actuated from any 120 suitable source of power but in the present instance of the invention it is provided with an arm 39, Fig. 4, to the end of which is pivotally connected the link 40 which at its upper end is pivoted to a rocker 41 mounted 125 to rock upon the stud or shaft 24, Fig. 4, and carrying a pin or roller 42 Fig. 5, traveling in the cam groove 43 of a cam 44 secured to the main shaft, the construction being such that as the main driving shaft 3 is con- 130

tinuously rotated, the actuating arm 14 of the feeding means and wedge carrying arm 30 will be reciprocated.

It is desirable, however, while the machine is running idly, that the work support be not given its feeding movements; and to this end the wedge plate 30, when the machine is running idly, is so related to its actuating means that it will not clamp the flange 28 of the carrying plate or member 13 to the actuating member 14 except when the fastenings are to be driven. In the present instance of the invention the block 35, Fig. 4, is connected by the links 45 to the arm 46 projecting from a rockshaft 47. The rock shaft 47 has secured thereto an arm 48 to which is pivotally connected the link 49, Fig. 4, the upper end of said link, Fig. 1, being connected to the bell crank lever 50 pivoted on the machine head at 51 and carrying a roll or pin 52 engaging the cam groove 53 in the cam disk 54, the construction being such that should the high part of the cam groove 53 engage the pin or roll 52 of the bell crank 50, the link 49 will be depressed and be held depressed so long as the pin or roll 52 is in engagement with the high part of the cam, to thereby move the block 35 upwardly in the slot 36, Fig. 4, and so relate the wedge plate to the pin 32 as that upon rocking movement of the shafts 18 and 38, in the manner hereinbefore described, the wedge 31 will cause the pin 32 to clamp the flange 28 of the carrying plate 13 or member of the work support and effect a feed movement thereof.

As fully described in the patent to Casgrain, No. 1,053,479, hereinbefore referred to, the fastening-inserting operations of the machine are under control of the two armed lever 55, Fig. 1, the arm 56 of said lever being normally in engagement with the toe or projection 57 as described in said patent when the machine is not driving the fastening. When the fastening-driving operation is to be started, the treadle 58 is depressed and through the treadle rod 59 connected at its upper portion at 60 to the arm 61, projecting from the two armed lever 55, 50 throws the arm 56 from under the finger or projection 57 and permits said finger or projection to move 180° until it contacts with and is stopped by the hook 62 on the other arm of the lever 55, substantially as pointed out and fully described in said Casgrain patent. When the projection or finger 57 moves 180°, as stated, the high portion of the cam 53 will ride under the pin or roller 52 of the bell crank 50 and cause a depression of the link 49 and corresponding lifting movement to be imparted to the block 35, whereupon the functional operation of the feeding means will be inaugurated.

When a shoe is placed upon the work support it is desirable that the work support be

freely movable to place the edge contour of the work against the edge gage. The movement thus imparted to the work support will vary, of course, in accordance with the size or dimension of the work itself. 70 After the work has been placed upon the edge gage, however, it is desirable that the feeding movements of the work support be made in a path substantially the same as the contour of the work, and that during 75 such movement the work be held with yielding pressure against the edge gage.

To these ends, the present invention contemplates means for permitting free movement of the work support to place the work 80 against the edge gage while the machine is at rest, and upon starting the fastening-inserting operation, to place the work support under yielding tension against the edge gage. The means to these ends may be variously contrived, but in the present instance of the invention the work carrying plate or member 13 is provided on its under surface with a groove 63 which is shaped substantially in accordance with the general contour 90 outline of the heel of a shoe. This groove 63 may extend all the way about the end portions of the work carrying plate 13 in which case each end portion of the groove 63 will conform to the general outline 95 contour of a shoe, so that, regardless of which end portion of the plate is presented to the operative, a jacked shoe may be secured to the carrying plate ready for the fastening-inserting operations, as will more fully 100 appear.

The groove 63 of the carrying plate 13 is engaged with guiding and holding means which, in the present instance of the invention, comprise the pins or rolls 64, Fig. 2. 105 These pins or rolls are carried by a slide 65 mounted in suitable ways in the table 12, and the slide 65 has secured thereto one end of a spring 66, the other end whereof is connected to the upper end of a rocker arm 67 secured to the rock shaft 68, Fig. 3. From the construction described it will be apparent that if the rock shaft 68 is free, the slide 65 and perforce, the work carrying plate 13 may be moved bodily to carry the 110 work mounted on the work support toward and from the edge gage. If, however, the rock shaft 68 is turned clockwise, Fig. 3, to place the spring 66 under tension, and then locked, the work placed against the 115 edge gage will be held yieldingly against said edge gage during subsequent feeding operations of the work support.

The rock shaft 68, Figs. 4 and 8, is suitably mounted in bearing arms 69 extending 120 downwardly from the table 12. The rock shaft 68 has secured thereto the toothed segment 70 adapted to be actuated by a pawl 71 mounted on a pawl carrier 72, Fig. 8, loosely supported on the shaft 68 by the hub or 125

- collar 73. Extending from the sleeve 73 is an arm 74 to which is connected at 75 the upper portion of a link 76, the lower end portion of which is connected at 77, Fig. 4, 5 with an arm 78 extending from the rock shaft 47, the construction being such that when the rock shaft 47 is actuated by depression of the rod 49 as the machine is set in operation for the insertion of fastenings, 10 the pawl 71 will engage the teeth of the toothed segment and rock shaft 68 to place the spring 66 under tension and hold the work support with the work yieldingly pressed against the edge gage.
- 15 In order that the degree of tension to be placed upon the spring 66 may be readily adjusted, there is loosely mounted upon the shaft 68 an arm 79, Fig. 8, which carries a 20 plate 80 adapted to be positioned at different points along the toothed segment to determine the engagement and disengagement of the pawl with the toothed segment. This adjustment may be effected in any suitable manner, as for instance, by a rod 81 secured 25 at one end to the arm 79 and at the other end provided with the slotted member 82 adapted to be held in adjusted position by means such as the bolt 83. From the construction thus far described it will be apparent 30 that when the machine is at rest, that is, when the fastenings are not being inserted, the slide 65 and perforce, the work support, is freely movable to enable the work support to be manipulated and adjusted in 35 position to place the edge of the work against the edge gage, such movement also serving to adjust the operative relation of the feeding means and work support in accordance with the size of the work. When, 40 however, the machine starts into operation for the insertion of fastenings, the depression of the rod 49 causes the pawl 71 to actuate the toothed segment 70 and the rock shaft 68 clockwise, Fig. 3, and place the 45 spring 66 under suitable tension for holding the work against the edge gage. A suitable spring 84, Fig. 3, may be carried by the pawl carrier 72 and act upon the pawl 71 to hold it in operative position.
- 50 After each feed movement of the work support, it is desirable that the work support be held from accidental movement as the feeding means moves on its idle stroke. The invention contemplates in this respect, 55 means for preventing movement of the work support during such time, said means in the present instance of the invention comprising a clamp 85, Fig. 3, pivotally mounted at 86 upon the slide 65 and carrying a roll 60 87 which rides upon the top surface of a cam slide 88. The cam slide 88 is guided for movement transversely of the slide 65 in suitable ways 89 formed upon the slide 65, and is connected by an actuating link 90 65 with a rocker arm 91 pivotally mounted in
- a suitable bracket 92 projecting from the table 12. The lower portion 93 of the rocker arm 91 engages the upper end of an arm 94 secured to the rock shaft 38, the construction being such that as the rock shaft 70 is rocked to release the work support from control of the feeding means, the cam slide 88 is moved beneath the clamp 85 to cause its end portion which overlaps the work carrying plate 13 to press upon and lock 75 the said plate from movement.
- While placing a jacked shoe upon the work carrying plate or member 13, and while removing a jack therefrom, it is also desirable that the work carrying plate or 80 member 13 be locked from movement, and this is effected in the present instance of the invention by treadle controlled means comprising a rocker 95, Fig. 3, connected to the treadle rod 96 which is adapted to be actuated by the treadle 97. Rising from the rocker 95 is a finger 98, the upper end portion of which is adapted to engage a toe or finger 99 extending downwardly from the hub 100 mounted to rock in suitable bearings 101 on the table 12. The hub 100 has extending therefrom a clamp actuating arm 102, the end 103 of which is adapted to extend beneath the rearwardly-projecting portion of the clamp 85, Fig. 3, the construction being such that upon depression of the treadle 97 the rocker 95 will be actuated to cause the clamp 85 to clamp the work carrying plate and hold it from accidental movement while the jacks are being changed 95 on the plate. Upon release of the treadle 97 after the jacks have been changed, the work support is freed to be moved by the attendant to place the work on the work-support against the edge gage. 100
- When the machine is operating for the insertion of fastenings, and the block 35 is raised in the slot 36 of the arm 37 to effect operative relation of the wedge plate 30 and actuating arm 14 of the feeding means, it 110 is desirable that the block 35 be locked in such position so long as the insertion of fastenings continues, and to this end the rock shaft 47 has secured thereto a locking finger 104, Fig. 1, which is adapted to engage the outer edge portion of a lug 105 mounted on the starting rod 59 and normally held in raised position by a spring 106, one end of which rests upon a clamp 107 secured to the starting rod and the other end against the 115 lug 105. When the treadle is depressed for starting the fastening-inserting operation, the locking finger 104 will engage the outer end portion of the lug 105 and lock the block 35 in raised position; but when the treadle 120 is released, the lug 105 will be lowered to disengage the locking finger 104 to permit the block 35 to move downwardly in the slot 36 into inoperative position.
- Where the shoe support is not raised for 125 130

the insertion of fastenings and then lowered to permit the work to be fed, as in the illustrated form of the present invention, it is desirable to adjust the shoe on its support 5 in such position that when it is operatively related to the fastening-inserting mechanism, the foot plate may engage the surface into which the fastenings are to be inserted. In these respects the present invention 10 contemplates a novel form of jack and means for determining the jacked position of the shoe relative to the foot plate before the jacked shoe is placed in operative relation with the fastening-inserting mechanism. 15 The jack comprises a base portion 108, Figs. 9 and 10, which is adapted to be moved over the top surface of the work carrying plate or member 13 which normally maintains its operative relation with the machine elements. Rising from the base 108 of the jack, is the hollow support 109 in which is the longitudinally movable jack post 110. Mounted in the top of the jack post is the rocker 111 from which extends 20 the last pin 112, a light spring 113 acting on the rocker 111 to maintain it normally in upright position. A spring 114 normally acts upon the jack post 110 tending to lift it. This spring may be of any usual character and as shown is of the spiral form, 25 one end of which is seated at the lower portion of the support 109 and the upper end against a block 115 mounted in the top portion of the jack post. The jack post is 30 guided in its movements in the support 109 by a pin 116 which passes through the support 109 and enters an elongated slot in the jack post as indicated in Fig. 10. The jack post has a series of teeth 117 which are 35 adapted to coact with corresponding teeth on a block 118 seated in a recess 119 formed in the support 109, said block being normally 40 under the action of a spring 120.

Extending from the base 108 of the jack 45 is a sleeve 121 from which projects a rod 122 having adjustably mounted thereon the sleeve 123 carrying the toe support. In the present instance of the invention the sleeve has projecting upwardly therefrom the exteriorly-threaded hollow post 124 in the hollow portion of which is received the rod 125 extending downwardly from the upper portion 126 of the toe support. Surrounding the exteriorly threaded hollow post 124 50 is the interiorly threaded sleeve 127. The upper portion of the sleeve 127 has a series of notches 128 with any one of which a pin 129 carried by the rod 125 or the head of the toe support may engage, the construction 55 being such that upon rotation of the sleeve 127 the toe support may be raised or lowered to adjust properly the height of the toe support for contact of the work being treated. The notches 128 in the sleeve have 60 rounded side portions so that while the pin

129 serves to lock the sleeve from rotation under any usual disturbing cause, it permits the sleeve to be rotated on the application of suitable force. The toe support may be properly faced with a suitable pad or 70 other yielding substance 130 to prevent injury to the toe portion of the shoe, and the rod 125 which is secured to the toe support as by means of the pin 131, is prevented from rotating in the sleeve 124 by a pin and 75 slot connection.

Secured to the rod 122 is a clamp 132 having secured thereto the arms 133 provided with notches 134 adapted to engage under lugs 135 secured to and projecting 80 upwardly from the carrying plate or member 13. In order that the jack may be readily applied to and disconnected from the carrying plate 13, the arms 133, of which there may be two, one at each side of the 85 jack, are preferably formed yielding, but of sufficient stiffness to hold the jack in proper operative position on the carrying plate.

Mounted for rocking movement in suitable bearings formed in the base portion of 90 the jack is a shaft 136 extending transversely thereof and having secured thereto the block supporting member 137, the portion 138 of which is connected as by the rounded portion 139 with the block 118, 95 the construction being such that the spring 120 acting on the block 118 will normally force the block to present its teeth into locking engagement with the teeth 117 on the jack post, to thereby hold the jack post in 100 raised position; but should the shaft 136 be rocked clockwise, Fig. 10, such rocking movement will carry the block 118 to the right out of locking engagement with the teeth 117 of the jack post, thereby permitting 105 the jack post to be controlled by the spring 114 alone.

Loosely mounted upon the rock shaft 136 are the side arms 140 of the heel seat clamping member 141, the upper portions 142 of 110 which are adapted to receive between them the rear portion of the shoe, substantially as indicated in Figs. 9 and 10. The inner surfaces of the upper portions 142 of the clamping member may be suitably lined with a 115 non-abrasive material 143 to prevent injury to the upper of the shoe.

Mounted for longitudinal movement in the heel seat clamping member 141 is the plunger 144 which is normally under the 120 influence of a spring 145 tending to move the plunger downwardly and its lower end 146 into contact with a ledge or projection 147 extending from the base portion of the jack.

Pivottally mounted on the heel seat clamping member 141 is a holding pawl 148 normally under the influence of a spring 149 tending to move the upper end 150 of the pawl into engagement with a recess 151 formed in the plunger 144, and its lower 130

hooked end 152 into engagement with the under surface of the locking shoulder 153 formed on the base of the jack.

Mounted on the end portions of the rock shaft 136 are the disks 154, Fig. 9, provided with the notches 155 in which ride the pins 156 carried by the arms 140 of the heel seat clamping member. These notches 155 are sufficiently large to permit considerable movement of the heel seat clamping member about the axis of the shaft 136 without the pins 156 engaging the shoulders at the end portions of the notches; but when the heel seat clamping member is moved into its fully-inoperative position as indicated by the dotted lines in Fig. 9, the pins 156 meet the shoulders of the notches 155 and turn the shaft 136 clockwise, Figs. 9 and 10, thereby withdrawing the locking block 118 from its engagement with the teeth 117 of the jack post, and freeing the latter. When the heel seat member has thus been moved to its fully-inoperative position, it is desirable that it be held in such position while the shoe is being placed upon the jack post. To this end the hook 152 of the holding pawl 148 engages beneath the shoulder 153 formed on the base of the jack and the end 150 thereof engages in the notch 151 of the plunger 144, thus relieving the heel seat clamping member from the full stress of the spring 145 and maintaining said member in fully-inoperative or dotted line position as indicated in Fig. 9. The formation of the holding pawl and the notch 151 and locking shoulder 153 are such that by slight effort the heel seat clamping member may be moved from its inoperative or dotted line position, Fig. 9, to its full line position.

Pivotal mounted upon the heel seat clamping member at 157 is a toggle jacking member. In the present instance of the invention this comprises a hand grip 158 having pivoted thereto at 159 a jacking pawl 160 normally under the influence of a light spring 161. The plunger 144 is provided with a series of teeth 162 adapted to be engaged by the jacking pawl 160, the construction being such that when the hand grip 158 is moved to the right, or contra-clockwise, about its pivotal mounting 157, Fig. 10, the jacking pawl 160 is removed from the teeth 162 and the heel seat clamping member may be moved readily into its full inoperative position. When a shoe has been placed upon the last pin with its toe resting upon the toe rest, and it is to be jacked, the heel seat clamping member is moved from the dotted to the full line position, Figs. 9 and 10, to cause the side members 142 to embrace the rear portion of the shoe between them and force the toe of the shoe upon the toe rest. The hand grip 158 is then moved to the left or clockwise about its pivotal mounting 157, whereupon the end of the pawl 160 en-

gages the teeth 162 of the plunger 144 and imparts to the heel seat clamping member a further jacking movement by the toggle action of the jacking pawl 160 and hand grip 158.

In order that the shoe may be jacked upon its support at a proper height to be placed upon the work carrying plate with the tread surface of the heel beneath the foot plate of the machine, the present invention contemplates a gage for determining the height of the shoe on the jack suitable to enable the shoe to be placed in operative position. This gage, in the present instance of the invention, comprises an arm 163 mounted on the upper end of a rod 164 adjustably carried by a block 165 formed on or secured to the side table 166. The gage 163 may be adjusted with respect to the surface of the side table 166 such that the distance between the surface of the table and the surface of the gage corresponds to the distance between the surface of the work carrying plate 13 and the foot plate of the machine; consequently when a shoe is placed upon the jack, which is done when the heel seat clamping member is in full inoperative position and the jack post 110 is unlocked, the tread surface of the heel of the shoe mounted upon the last pin of the jack post may be permitted to rise, under the action of the spring 114 until the tread surface of the heel meets the gage 163, whereupon the heel seat clamping member will be turned from its full inoperative position, dotted lines Fig. 9, into its full line or jacking position, at which time movement of the hand grip 158 clockwise about its pivotal mounting 157 imparts a toggle action to the pawl 160 to give an additional jacking movement to the heel seat clamping member to securely jack the shoe.

While the attendant is jacking a shoe as above explained, the machine may be inserting fastenings in a shoe supported by another jack secured to the work carrying plate; and when the fastening-inserting operation has been completed, the attendant may readily detach the jack carrying the shoe having the fastenings inserted therein from the work carrying plate and substitute therefor the shoe which he has just jacked. If the jack holding the freshly jacked shoe were presented to the machine in the same relation to the table 13 as the jack supporting the finished shoe, the contour edge of the heel of the shoe in the continued operation of the machine, would be carried away from the fastening inserting instrumentalities, inasmuch as the table 13 is rotated continuously in the same direction. Consequently, it is contemplated that the jacks and the shoes supported thereby will be presented to the table 13 in alternately reversed relations, and since the rolls 64 are disposed substantially in the middle of the relatively

straight portions of the groove 63 at the sides of the table 13 at the end of each fastening inserting operation on a shoe a heel will thus be operatively presented to the fastening inserting instrumentalities during substantially every part of the cycle of movement of the table 13.

What is claimed is:—

1. In a fastening inserting machine the combination with a work support for sustaining a shoe for the insertion of fastenings, of means for feeding the work support variable angular amounts determined by a dimension of the shoe to insure similar intervals between fastenings in shoes of different dimensions.
2. In a machine of the character described, the combination with means for operating on a shoe and a work support movable into operative relation with said means for supporting a shoe for operation thereon by said means, said work support being freely movable in a direction to feed the work, of means for feeding the work support angular amounts determined by a dimension of the shoe as the shoe support is moved into operative relation to the operating means.
3. In a machine of the character described, the combination with means for operating on a shoe and a work support movable into operative relation to said means for supporting a shoe for operation thereon by said means, of means for imparting angular step-by-step feed movements to the work support, and work positioning means for determining by reference to a dimension of the work the operative position of the work and the angular movement to be imparted to the work support by the feeding means.
4. In a fastening inserting machine, the combination with a work support for supporting a shoe for the insertion of fastenings, of feeding means for imparting angular step-by-step feed movements to the work support, and means for determining by a dimension of the work the degree of the angular step-by-step movements imparted to the work support by the feeding means.
5. In a machine of the character described, the combination with means for operating on a shoe and a shoe support freely movable in a direction to feed the work; of feeding means for moving the shoe support angularly step-by-step, means permitting the operative relation of the shoe support and feeding means to be varied as the shoe support is moved into operative relation to the operating means, and means acting through a dimension of the work for determining the amplitude of the angular step-by-step movements imparted to the work support by the feeding means.
6. In a fastening-inserting machine, the combination of a work support for sustaining a shoe for the insertion of fastenings, feeding means for moving the work support angularly substantially in conformity with the contour of the work, and means for varying the angular movement of the work support by the feeding means to a degree depending upon the difference in size of the work to preserve the same distance between adjacent fastenings in shoes of different sizes.
7. In a fastening-inserting machine, the combination of a gage, a shoe support freely movable in the direction of feed of the shoe; means permitting movement of the shoe support toward the gage, feeding means for moving the shoe support angularly step-by-step to move the work along the gage, and means between the shoe support and feeding means for changing the amplitude of angular movement imparted to the shoe support by the feeding means to a degree dependent upon the difference in a dimension of the work.
8. In a fastening-inserting machine, the combination of a gage, a shoe support freely movable in the direction of feed of the shoe, feeding means for moving the shoe support angularly step-by-step, and operating connections between the feeding means and shoe support adjustable by movement of the shoe support into operative position to vary the angular movement imparted to the shoe support to a degree dependent upon the difference in the size of the work.
9. In a machine for inserting fastenings, the combination of a gage and a shoe support for positioning a shoe for the insertion of fastenings, and means for feeding the shoe support angularly in degrees determined by the positioning movement of the shoe support to place the shoe against the gage.
10. In a machine for inserting fastenings, the combination of a work support, continuously operating feeding means for said support constructed and arranged to feed the work support different angular amounts determined by a dimension of the work, and means for rendering the feeding means functionally operative to move the work support on starting the machine.
11. In a machine of the character described, the combination of a gage, a work support freely movable to place the work supported thereby against the gage while the machine is at rest, and means acting automatically when the machine is started to force the work yieldingly against the gage.
12. In a machine of the character described, the combination of an edge gage, a work support freely movable to place the work supported thereby against the edge gage while the machine is at rest, means acting automatically when the machine is started to force the work yieldingly against the edge gage.

- started to force the work yieldingly against the edge gage, and means for feeding the work support angular amounts determined by a dimension of the work and while the 5 work is yieldingly held against the edge gage.
13. In a machine for inserting fastenings, the combination of means for operating on a shoe, a shoe support for sustaining a shoe 10 and freely movable to and from operative relation with the operating means, and means rendered effective upon starting the machine to hold the shoe support yieldingly in operative relation to the operating means.
14. In a machine of the character described, the combination of means for operating on a shoe, a gage for determining the operative relation of the operating means and the work, a work support for supporting the shoe, a spring connected to the work support, and means for placing the spring under tension when the machine is started to maintain the shoe yieldingly in position for operation thereon by said operating 20 means and acting to release the spring tension when the machine is stopped, said means being constructed and arranged to permit the work support to be moved manually into operative relation to the operating 25 means without tensioning the spring.
15. In a machine for inserting fastenings, the combination of means for operating on a shoe, a shoe support for sustaining a shoe and freely movable to and from operative 30 relation with the operating means, and means rendered effective upon starting the machine to hold the shoe support yieldingly in operative relation to the operating means and to free the shoe support when the machine is stopped.
16. In a machine for inserting fastenings, the combination of a work support for sustaining a shoe for the insertion of fastenings freely movable in the direction of feed 45 of the work, feeding means for moving the shoe support in a path substantially conforming to the contour of a shoe part, and means for causing the feeding means to be operatively related to the work support at 50 different distances from its center of movement as determined by a dimension of the work.
17. In a machine for inserting fastenings, the combination of a work support for sus- 55 taining a shoe for the insertion of fastenings, feeding means for moving the shoe support in a path substantially conforming to the contour of a shoe part, means for causing the feeding means to be operatively 60 related to the work support at different distances from its center of movement as determined by a dimension of the work, and means for preventing movement of the work support between feed movements.
18. In a machine of the character de- 65 scribed, the combination with means for operating on a shoe and a shoe support for sustaining a shoe for operation thereon by said operating means, of means for feeding the work support variable angular amounts 70 determined by a dimension of the work to insure similar intervals between the points of operation on shoes of different dimensions, and means for preventing movement of the work support between feed move- 75 ments.
19. In a machine of the character de- 80 scribed, the combination with means for operation on a shoe and a shoe support movable into operative relation to said mechanism for supporting a shoe for operation thereon by said operating means, of feeding means for imparting angular step-by-step feed movements to the work support, means for preventing movement of the work support between feed movements, and means for determining by a dimension of the work the degrees of angular step-by-step 85 movements imparted to the work support by the feeding means. 90
20. In a machine for inserting fastenings, the combination of a work support for positioning the work, feeding means for moving the work support angularly step-by-step, means for clamping the work support against movement, and automatic means independent of the feeding means for causing the clamp to hold the work support between feed movements. 95
21. In a machine for inserting fastenings, the combination with a work support, of continuously actuated feeding means for the work support rendered effective upon starting the machine to move the work support angular amounts determined by a dimension 100 of the work. 105
22. In a machine for inserting fastenings, the combination of a work support, continuously actuated means for feeding the work support angular amounts determined by a 110 dimension of the work, and wedge means for rendering the feeding means functionally operative upon starting the machine.
23. In a machine for inserting fastenings, the combination of a work support freely 115 movable in the direction of feed of the support, an actuating arm for feeding the work support angular amounts determined by a dimension of the work, and means for rendering said arm functionally effective to 120 move the work support on starting the machine.
24. In a machine for inserting fastenings, the combination of a work support, continuously operated means for feeding the work 125 support constructed and arranged to be operatively disconnected from the support when fastenings are not being inserted by the machine, means for connecting the feeding means with the support, and means nor- 130

- 5 mally stationary during the operation of the machine for rendering the connecting means functionally effective to connect the feeding means with the support on starting the machine.
- 6 25. In a machine for inserting fastenings, the combination of a work support, continuously actuated means for feeding the work support, and a continuously actuated mem- 70 ber for rendering the feeding means effective only when the fastening-inserting operations are started.
- 10 26. In a machine for inserting fastenings, the combination with a work support, of 75 continuously actuated feeding means for the work support rendered effective upon start- 80 ing the machine to move the work support angular amounts determined by a dimension of the work, and automatic means for clamp- 85 ing the work support after a feed-movement.
- 15 27. In a machine of the character de- 90 scribed, the combination of means for oper- 95 ation on a shoe, a shoe support, means for feeding the shoe support for operation on the shoe by said operating means, and means in guiding engagement with the shoe support for directing the feed movements of the support in a path substantially in conformity with the contour of the shoe part 100 upon which operations are being per- 105 formed, said means being constructed and arranged to permit movement of the shoe support at the point of its guiding engagement therewith angularly of the direction 110 of feed of the support and to retain its guid- 115 ing engagement with the support during such movement.
- 20 28. In a fastening inserting machine, the combination of a carrying plate, a jack 120 adapted to be carried by said plate and to support a shoe, means for feeding the carrying plate for the successive insertion of fastenings into the shoe supported by the jack, and means acting on the carrying plate 125 for directing its feed movements in a path substantially in conformity with the con- 130 tour of the shoe part into which the fastenings are to be inserted, said means being movable to shift the carrying member trans- 135 verse to the direction of angular movement of the plate.
- 25 29. In a fastening inserting machine, the combination of a shoe support comprising a carrying plate and jack, said carrying plate 140 having a guide conforming substantially to the contour of the shoe part into which the fastenings are to be inserted, means for feed- 145 ing the plate and jack, and means engaging the guide to direct the feed movements in a path substantially conforming to the con- 150 tour of the shoe part, said means being movable to shift the carrying plate transverse to the direction of feed of the plate.
- 30 30. In a fastening inserting machine, the combination of a shoe support comprising a carrying plate and jack, said carrying plate 155 having a guide conforming substantially to the contour of the shoe part into which the fastenings are to be inserted, said carrying plate 160 having a guide conforming substantially to the contour of the shoe part into which the fastenings are to be inserted, means for feed- 165 ing the plate and jack, and means for feed- 170 ing the plate and jack, and yielding means 175 having positive engagement with the guide to direct the feed movements in a path sub- 180 stantially conforming to the contour of the shoe part.
- 35 31. In a machine of the character de- 185 scribed, the combination of means for oper- 190 ating on a shoe, an edge gage, a shoe support for supporting a shoe for operation thereon by said operating means, feeding means for the work support, and means for guiding 195 the feed movements of the work support in a path conforming substantially with the contour of the work, said means being movable to shift the work support in a direction 200 toward and from the edge gage. 85
- 40 32. In a machine of the character de- 205 scribed, the combination of means for oper- 210 ating on a shoe, an edge gage, a work support for supporting a shoe for operation thereon by said operating means, means for guiding 215 the feed movements of the work support in a path conforming substantially with the contour of the work and permitting bodily movement of the work support in a direction 220 toward and from the edge gage, and feeding 225 means for moving the work support angular amounts determined by a dimension of the work. 90
- 45 33. In a fastening inserting machine, the combination of a jack carrying plate having 230 a guide conforming substantially to the con- 235 tour of a shoe part into which the fastenings are to be inserted, a slide in operative engage- 240 ment with the guide for directing the move- 245 ment of the jack carrying plate, means for placing the slide under yielding tension when the machine is started, and a gage against 250 which the work is yieldingly held by said slide. 100
- 50 34. In a machine of the character de- 255 scribed, the combination of means for oper- 260 ating on a shoe, a work support comprising a jack carrying plate, a movable machine part coöperating with the plate to guide the feed movements thereof in a path conform- 265 ing substantially with the contour of the work, and ratchet and pawl mechanism for placing the movable part under yielding tension to hold the work in operative position 270 when the machine is started. 110
- 55 35. In a machine of the character de- 275 scribed, the combination of a continuously- 280 actuated driving shaft, means for operating on a shoe, a work support for supporting the work for operation thereon by said op- 285 erating means, feeding means for the work support continuously actuated from the driv- 290 ing shaft, and automatic means for render- 295 ing the work support effective to connect the feeding means with the support on starting the machine. 115

- ing the feeding means effective for feeding the work support when the machine is started.
36. In a machine of the character described, the combination of means for operating on a shoe, a jack carrying plate, means for detachably securing a jack with a shoe in jacked position thereon to said carrying plate that the attendant may jack one shoe during operation on another jacked shoe, means for effecting uni-directional movement of the carrying plate to feed the work and means for constraining the ends of the carrying plate to move through substantially the same path so that part of a shoe mounted on one jack may be presented to the operating means when one end of the carrying plate is traversing said path and a corresponding part of a shoe on another jack may be presented to the operating means when the other end of the carrying plate traverses said path.
37. In a machine for inserting fastenings, the combination of means for operating on a shoe, a substantially symmetrical jack carrying member comprising two perverted parts, a jack, means acting on the jack carrying member to impart a uni-directional movement to said member to feed the work mounted on the jack, means for constraining the ends of said member to move through substantially the same path, and means for securing jacks on the carrying member in alternately reversed relations to the member so that corresponding parts of different shoes may be presented in like manner to the operating means during a complete rotation of said member.
38. In a machine for inserting fastenings, the combination of means for operating on the heel of a shoe, a jack carrying member having a substantially symmetrical guiding portion comprising two perverted parts each shaped correspondingly to the contour of a heel, a jack, means for operatively positioning jacks in alternately reversed relations on the jack carrying member by sliding movement of the jacks and locking the jacks in such position, and means for imparting uni-directional movement to the carrying member to feed the work relatively to the operating means.
39. In a machine for inserting fastenings, the combination of means for operating on a shoe, a jack carrying member formed to provide a substantially symmetrical groove comprising two perverted portions each shaped correspondingly to the contour of a heel, a device for guiding said member by engagement in said groove, a jack, means for operatively positioning jacks in alternately reversed relations on the jack carrying member by sliding movement of the jacks and locking the jacks in such position including a spring clip, and means for imparting uni-directional movement to the carrying member to feed the work relatively to the operating means.
40. In a machine of the character described, the combination of means for operating on a shoe, a jack carrying member, a jack adapted to have a shoe jacked thereon while separate from the jack carrying member, means for locking the jack carrying member from movement while the jack is being applied to the jack carrying member, and means acting upon the jack carrying member to give the work on the applied jack its feed movements.
41. In a machine of the character described, the combination of means for operating on a shoe, a jack carrying member, a jack adapted to have a shoe jacked thereon while separate from the jack carrying member, treadle controlled means for locking the jack carrying member from movement while the jack is being applied to the jack carrying member, and means acting upon the jack carrying member to give the work on the applied jack its feed movements.
42. In a machine for inserting fastenings, the combination of means for operating on a shoe, a fixed table, a jack carrying member mounted for feed movements on said table to present different portions of the shoe to the operating means, a jack adapted to be applied to the jack carrying member, and means for jacking a shoe on the jack in predetermined position to enable the jacked shoe to be applied to the carrying member beneath the operating means.
43. In a machine for inserting fastenings, the combination of means for operating on a shoe, a fixed table, a jack carrying member mounted for feed movements on said table relative to the operating means, a jack adapted to be applied to the jack carrying member, means for jacking the shoe on the jack while separate from the jack carrying member, and a gage to determine the jacked position of the shoe that it may be applied to the jack carrying member between it and the operating means.
44. In a machine of the character described, a work support comprising a toe rest and spring supported jack post, a heel seat clamping member movable to and from jacking position, means actuated when the heel seat clamping member is moved from unjacked to jacked position to lock the jack post, and toggle means connected to the heel seat clamping member for imparting additional jacking movement to said member.
45. A work support comprising a toe rest, a last pin for engaging the last pin socket of a last, a yieldingly mounted jack post carrying the last pin, a heel seat clamping member mounted to swing to and from a

shoe mounted on the last pin, means for locking the jack post when the heel seat clamping member is moved to engage the shoe, and means acting upon the heel seat clamping member to press upon the heel portion of and to jack the shoe.

46. A work support comprising, in combination, a yieldingly mounted jack post, a last pin carried by the post to be engaged with the last pin socket of a last, a heel seat clamping member, a plunger, means normally acting upon the plunger to move the heel seat clamping member into jacking position, and toggle means adapted to implement a further jacking movement to the heel seat clamping member.

47. A work support comprising, in combination, a jack post, a last pin carried by the jack post, a heel seat clamping member mounted to swing to and from jacking position, a plunger carried by the heel seat clamping member and acting normally to swing the heel seat clamping member into jacking position, and toggle means adapted to act through the plunger when the shoe is jacked to give additional jacking movement to the heel seat clamping member.

48. A work support comprising, in combination, a jack post, a last pin carried by the jack post, a heel seat clamping member mounted to swing to and from jacking position, a plunger carried by the heel seat clamping member and acting normally to swing the heel seat clamping member into jacking position, and manually operated toggle means adapted to act through the plunger when the shoe is jacked to give additional jacking movement to the heel seat clamping member.

49. A work support comprising, in combination, a yieldingly mounted jack post carrying a last pin, a lock for the jack post, a heel seat clamping member movable to and from jacking position, and connections between the heel seat clamping member and lock for operating the latter as the said member is moved to and from jacking position.

50. In a machine of the class described, a work support comprising a base and a jack post movably mounted thereon, a heel clamping member, and means controlled by the heel clamping member for locking the jack post against movement.

51. A work support comprising, in combination, a toe rest and a yieldingly mounted jack post carrying a last pin, a lock for the jack post, a heel seat clamping member movable to and from jacking position, means normally acting on the heel seat clamping member for moving it to jacking position, and connections between the heel seat clamping member and lock for releasing the jack post as the clamping member is

moved into unjacking position and permitting locking engagement of the lock and jack post as the heel seat clamping member is moved to jacking position.

52. A work support comprising, in combination, a toe rest and jack post, a last pin carried by the jack post, a heel seat clamping member mounted to swing to and from jacking position, a plunger carried by the heel seat clamping member and normally tending to move the clamping member into jacking position, a series of teeth formed on the plunger, and manually operated toggle means acting on the teeth and through the plunger to impart additional jacking movement to the heel seat clamping member when the latter is in jacking position.

53. A work support comprising, in combination, a toe rest and jack post, a last pin carried by the jack post, a heel seat clamping member mounted to swing to and from jacking position, a plunger carried by the heel seat clamping member and normally tending to move the clamping member into jacking position, a series of teeth formed on the plunger, a hand grip pivotally connected to the heel seat clamping member, and a pawl carried by the hand grip to engage the teeth on the plunger when the clamping member is in jacking position to give additional jacking movement to the clamping member.

54. In a work support, the combination of a toe rest, a jack post, a lock for the jack post, a heel seat clamping member mounted to swing to and from jacking position, and a catch for holding the heel seat clamping member and jack post lock in inoperative position.

55. In a work support, the combination of a toe rest, a jack post, a lock for the jack post, a heel seat clamping member mounted to swing to and from jacking position, a spring actuated plunger normally acting to move the heel seat clamping member into jacking position, and a catch for holding the jack post lock and heel seat clamping member in inoperative position.

56. In a machine of the class described, a work support comprising a base, a jack post slidably mounted on said base, means for yieldingly urging the jack post from the base of the support, means for locking said post against movement, and manually controlled means constructed and arranged for engagement with the work on the jack post and operable to move the locking means into and out of operative relation to the jack post.

57. A work support of the class described comprising a heel seat clamping member, means acting normally to urge the clamping member against a shoe on the support,

- and means carried by the clamping member for effecting additional movement of the member. 45
58. A work support of the class described 5 comprising a heel seat clamping member, a plunger slidably in the clamping member, and means carried by the clamping member and operable on the plunger for forcing the clamping member against a shoe on the support. 50
59. A work support of the class described comprising a base, a heel seat clamp pivotally supported on the base, a member shaped for manipulation by the operator and movable bodily to swing the clamp toward and away from a shoe on the support, and means operable by said member to press the clamp firmly into engagement with the shoe. 55
60. A work support of the class described 20 comprising a base, a heel seat clamp pivotally supported on the base, a plunger slidably mounted in the clamp and having one of its ends disposed in engagement with the base, a spring interposed between the clamp and said plunger and tending to move the clamp toward a shoe on the support, a hand grip pivotally connected to the clamp for bodily movement therewith, and a pawl carried by the hand grip and operable on the plunger to press the clamp firmly into engagement with the shoe. 60
61. A work support of the class described comprising a base, a heel seat clamp movable on said base between operative and inoperative positions relatively to a shoe on the support, a spring tending to move the clamp into engagement with the shoe, and a catch for holding the clamp in inoperative position. 70
62. A work support of the class described 35 comprising a base, a heel seat clamping member movable on said base between operative and inoperative positions relatively to a shoe on the support, a plunger slidably mounted in the heel seat clamping member, a spring interposed between the clamping member and the plunger, and a catch for securing the heel seat clamping member to the base and the plunger to hold it in inoperative position. 75
63. A work support of the class described comprising a base, a heel seat clamping member pivotally supported on said base, a plunger slidably mounted in the clamping member, a spring interposed between the plunger and the clamping member and tending normally to press the clamping member against a shoe on the support, and a catch for locking the clamping member and the plunger together. 80
64. A work support of the class described comprising a post, a toe rest mounted on the post for sliding movement relatively to the post, connections between the toe rest and the post for preventing relative angular movement of the toe rest and the post, and a supporting sleeve for the toe rest threaded on the post so that the toe rest may be adjusted by rotation of the sleeve on the post. 85
65. A work support of the class described comprising a post, a toe rest mounted on the post for sliding movement relatively to the post, connections between the toe rest and the post for preventing relative angular movement of the toe rest and the post, a pin on the toe rest, and a supporting sleeve for the toe rest threaded on said post and formed with notches adapted to receive the pin on the toe rest so that the toe rest may be adjusted and secured in adjusted position by rotation of the sleeve on the post. 90

In testimony whereof I have signed my name to this specification.

LOUIS A. CASGRAIN.

It is hereby certified that in Letters Patent No. 1,361,013, granted December 7, 1920, upon the application of Louis A. Casgrain, of Beverly, Massachusetts, for an improvement in "Machines for Inserting Fastenings," errors appear in the printed specification requiring correction as follows: Page 9, lines 78-79, claim 19, and page 10, lines 22-23, claim 27, for the word "operation" read *operating*; and that the said Letters Patent should be read with these corrections therein that the same may conform to the record of the case in the Patent Office.

Signed and sealed this 5th day of April, A. D., 1921.

[SEAL.]

M. H. COULSTON,

Commissioner of Patents.

Cl. 12—127.
